UNITED STATES PATENT OFFICE.

MAURICE TAUSSIG, OF CHICAGO, ILLINOIS.

DESIGN FOR A LEG FOR STORE FURNITURE.

43,169.

Specification for Design.

Patented Oct. 15, 1912.

Application filed May 25, 1912. Serial No. 699,762. Term of patent 7 years.

To all whom it may concern:

Be it known that I, MAURICE TAUSSIG, a citizen of the United States, residing at Chicago, in the county of Cook and State of Illinois, have invented a new, original, and ornamental Design for a Leg for Store Furniture, of which the following is a specification, reference being had to the accompanying drawing, forming part thereof.

Figure 1 is an elevation of a leg for store furniture looking at the corner thereof, and showing my new design, Fig. 2 is a side elevation thereof and Fig. 3 is an end view looking from the bottom.

I claim:

The original design for a leg for store furniture as shown.

MAURICE TAUSSIG.

Witnesses:

WALTER J. FLESCH,
E. J. MASSMAN.
